UNITED STATES PATENT OFFICE.

FRANK J. DIACONT, OF PROVIDENCE, RHODE ISLAND, ASSIGNOR TO HENRY H. CURTIS, OF NORTH ATTLEBOROUGH, MASSACHUSETTS.

DESIGN FOR A HANDLE FOR BUTTON-HOOKS OR SIMILAR ARTICLES.

SPECIFICATION forming part of Design No. 29,018, dated July 12, 1898.

Application filed June 10, 1898. Serial No. 683,138. Term of patent 7 years.

To all whom it may concern:

Be it known that I, FRANK J. DIACONT, a citizen of the United States, and a resident of the city and county of Providence, State of Rhode Island, have invented a new and original Design for Handles for Button-Hooks or Similar Articles, of which the following is a specification, reference being had to the accompanying drawing, forming part thereof, which shows the article in elevation.

In the figure shown the material features of my design may be described as follows:

The base of the handle is a mass of foliates 1, from which arises a gradually-broadening octagonal shaft ornamented by rows of spherical beads 2 throughout its length. Diverging foliated scrolls 3 give the middle of the handle a swelled outline. From this swell the width of the handle suddenly diminishes, and thereafter gradually expands outward and upward to form the head 5. The base of this head is formed by an upright group of foliates 6, flanked by the oppositely-disposed scrolls 4, the longer members of which, 7, embrace the plain panel 8 and are bordered upon their inner edges by rows of spherical beads 11. The crest is formed by reversely-curved scroll ornaments 9 on opposite sides of the upright group of foliates 10.

Having described my invention, what I claim as new, and desire to secure by Letters Patent, is—

The design for a handle for button-hooks or similar articles, substantially as herein shown and described.

In witness whereof I have hereunto set my hand.

FRANK J. DIACONT.
